ANIMAL RESTRAINER

William S. Koon, Harford County, and Nelson P. Musselman, Baltimore, Md., assignors to the United States of America as represented by the Secretary of the Army

Filed Mar. 14, 1963, Ser. No. 73,998

Term of patent 14 years

(Cl. D12—2)

(Granted under Title 35, U.S. Code (1952), sec. 266)

The invention shown herein may be manufactured and used by or for the Government of the United States of America for governmental purposes without the payment to us of any royalty thereon.

The drawing is a perspective view of the animal restrainer showing our new design.

The essential features of the design reside in the portions shown in full lines.

The showing of the dog in broken lines is for illustrative purposes only.

The undisclosed side is substantially the same in appearance as the side shown.

We claim:

The ornamental design for an animal restrainer, as shown and described.
